[57] CLAIM

The ornamental design for writing surfaces and container for supplies, as shown and described in the drawings.

DESCRIPTION

FIG. 1 is a perspective view of the writing surfaces and container for supplies showing our new design in an opened condition;

FIG. 2 is a top plan view;

FIG. 3 is a first side elevational view;

FIG. 4 is a second side elevational view;

FIG. 5 is a third side elevational view;

FIG. 6 is a fourth side elevational view;

FIG. 7 is a bottom plan view; and,

FIG. 8 is a perspective view thereof in a closed condition.

The textured patterning is continuous throughout the outer surfaces as shown.

FIG. 1

FIG. 7

FIG. 8
